In Great Britain October 25, 1944

4 Claims. (Cl. 57—54)

1

This invention relates to flyer spinning, twisting and like textile frames, and especially to mechanism for aligning the legs of the flyers so as to allow packages of spun or twisted yarn to pass out from between the legs of the several flyers without interference when manipulating the doffing mechanism.

The object of the invention is to provide a simple flyer-leg-aligning mechanism contrived to avoid the application of excess thrust on flyers which have stopped in dead-centre position.

Flyer-leg-aligning mechanism according to the invention includes, for each flyer, a yieldable member which is movable into engagement with a leg of the respective flyer and which is deflectable thereby when the leg is in dead-centre position, whereby said yieldable member is enabled to exercise a turning moment on the flyer.

In practice, we may make use of levers mounted on a bar movable transversely towards and from the flyers. When the machine is stopped for doffing, the flyer legs may come to rest in such a position that the bar may easily bring about alignment, but when the legs of a flyer come to rest in a position transverse to the path of the bar, the respective lever will take up such a position as to impart the necessary turning moment to the flyer and so align the flyer, the aligned flyers being then firmly held in position by the bar.

In order that the nature of the invention may be properly understood, one construction will now be described with reference to the accompanying drawing in which Fig. 1 is a front elevation of the upper part of a flyer spinning frame, and Fig. 2 is a plan view of the parts shown in Fig. 1. Fig. 3, Fig. 4 and Fig. 5 show a movable lever in three positions as it gradually aligns a flyer.

The part of the spinning frame shown in the drawings has depending flyers 1 mounted in ball bearings in spaced relation and supported by an overhead rail 2. The flyers 1 are rotated by tapes driving the wharves 3 in usual manner. When the machine is stopped for doffing, the flyer legs 4 may stop in any position such as 4¹, 4² or 4³, and it is therefore necessary to bring all the flyer legs into alignment, such as in position 4³, to allow the packages 5 of yarn to pass out from between the legs 4 of the several flyers without interference. We employ a horizontal bar 6 which extends from end to end of the machine and which is carried by toothed racks 7 mounted on the bearers of the machine. The bar 6 is held behind the flyers 1 and is clear of the flyers when the machine is running, but, when the machine

2

is stopped, the bar can be moved forward towards the flyers by rotation of the shaft 8 which extends from end to end of the machine, and which carries pinions 9 meshing with the racks 7. The shaft 8 is rotatable by operation of the hand lever 10. On the bar 6 are mounted brackets 11 to each of which is pivoted a V-shaped lever 12 having an inwardly extended arm 12¹ connected to the bracket 11 by a spring 13. The spring 13 pulls the lever against a stop 14; a stop 15 limits the movement of the lever 12 in the opposite direction. Should a flyer 1 stop in a position such as 4¹, then the bar 6 when moved forward will align the legs into the position shown at 4³. Should the flyer legs come to rest in oblique position relative to the path of the bar 6, then the V-shaped lever, when brought forward with the bar 6, will exercise the necessary turning moment on the flyer. The most difficult approach of the lever 12 is shown at Fig. 3, when the flyer stops in direct centre position, and when the summit 12² of the V comes in contact with the flyer leg in such a position that the force applied by the bar 6 would be acting through the axis of the flyer. In this case the lever 12 moves into the position shown in Fig. 4, the turning moment is applied to the flyer, and the bar 6 in continuing its forward motion aligns the flyer as shown by Fig. 5. The spring 13 restores the lever 12 to its initial position when the lever 12 has completed its action on the flyer. The bar 6 when in forward position abutting against the flyers as shown in Fig. 5 holds the flyers securely in aligned position.

35. What is claimed is:

1. In spinning, twisting, and like textile frames having a row of flyers each having a pair of legs, flyer-leg-aligning mechanism including, for each flyer, a yieldable member, means for moving said member into engagement with a leg of the respective flyer, said member adapted to yield if said leg is in dead-centre position, and means limiting the yielding movement of said member to enable said member to exercise a turning moment on the flyer.

2. Flyer-leg-aligning mechanism as claimed in claim 1 in which the yieldable members are of substantially V-form in plan and the means for moving said members comprises a bar on which said members are mounted in spaced relation, said bar being movable transversely of its length towards and away from the row of flyers.

3. Flyer-leg-aligning mechanism as claimed in claim 1, in which the yieldable members are of substantially V-form in plan and the means for

moving said members comprises a bar movable towards and away from the row of flyers, said bar having a set of stops, each of said members having an arm engageable with one of said stops, and a spring urging said arm towards said stop.

4. Flyer-leg-aligning mechanism as claimed in claim 1 in which the means for limiting the yielding movement of the yieldable member comprises a stop engageable by the yieldable member, and the means for moving said member comprises a 10 bar movable towards and from the row of flyers, said stop being carried by said bar.
